UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 14,470, dated December 11, 1883.

Application filed July 23, 1883. Term of patent 3½ years.

To all whom it may concern:

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

15 The ground consists of an irregular net-

work of angular stems bearing variously-shaped figures, as shown. Over this ground, and distinct from it, is a system of gem figures, some larger, some smaller, as shown. These gems may be connected by stem-work. 20 In the photograph they are represented as having no stem-connections.

I claim—

The design for a carpet, substantially as shown and described.

WINTHROP L. JACOBS.
